(57) **CLAIM**

The ornamental design for a combined utility light and docking station, as shown and described.

DESCRIPTION

FIG. 1 is a front perspective view of a combined utility light and docking station showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front perspective view thereof;

FIG. 10 is a rear perspective view thereof;

FIG. 11 is a front perspective view thereof, showing the utility light port cover in an open position;

FIG. 12 is an exploded, front perspective view thereof, the utility light and the docking station shown separated for clarity of disclosure;

FIG. 13 is an exploded, rear perspective view thereof, the utility light and the docking station shown separated for clarity of disclosure;

FIG. 14 is a rear perspective view of the utility light, showing the support member in a deployed position; and, FIG. 15 is a front perspective view thereof.

The broken lines in the drawings depict parts of the combined utility light and docking station that form no part of the claimed design.
